UNITED STATES PATENT OFFICE

GEORGE B. PERKINS, OF EUREKA, COLORADO

SAFETY DEVICE

Application filed January 5, 1929. Serial No. 330,654.

This invention relates to safety devices primarily adapted for use upon mine and other cars traveling upon inclined driveways.

An object of the invention comprehends a gripping element for the vehicle.

Another object of the invention contemplates a yielding element for the gripping element to normally induce same to occupy an operative position.

10 A further object of the invention consists in the provision of a connection between the vehicle draft appliance and the gripping element whereby the latter will be shifted for active use when the tongue, king bolt, cable, etc., is broken to prevent retrograde movement of the vehicle.

With the above and other objects in view, the invention further consists of the following novel features and details of construction to be hereinafter more fully described, illustrated in the accompanying drawing and pointed out in the appended claim.

In the drawing:—

Figure 1 is a side elevation of the invention.

25 Figure 2 is a top plan view thereof.

Referring to the drawing in detail, wherein like characters of reference denote corresponding parts, the reference character 10 indicates generally a mine or other car 30 traveling upon rails 11 and supported by ties 12. As heretofore experienced, the lives of mine workers in mine shafts are in constant jeopardy by the possibilities of the breaking of cables, tongues and other draft appliances 35 for the cars.

The present invention has been primarily designed to overcome this grave possibility and which comprises an equalizer bar, such as indicated at 13, having its ends slidably mounted within slots 14 in the side walls of 40 the cars.

Tongues 15, projecting at right angles and at intermediate points in the lengths of the equalizer bars 13, are projected through the 45 adjacent end walls of the cars for connection with cables or other draft appliances 16.

The connection between the equalizer bar 13 and the tongue 15 comprises an extension 50 15' projecting from the innermost end of the tongue and transversely through the inter-

mediate portion of the equalizer bar as shown in Figure 2 of the drawing. A shoulder 15², preferably of annular formation, carried by the tongue 15 at the intersection of the extension 15' therefor, is adapted to abut the 55 adjacent outer surface of the bar 13 about the opening therein receiving said extension.

A nut 15³ and washer 15⁴ are carried upon the innermost protruding and threaded end of the extension 15' to retain the tongue against displacement and provide a detachable connection therebetween.

Holding or gripping dogs 17, pivotally mounted for rocking movement, as at 18, upon trunnions 18' having attaching flanges 60 65 18² upon the innermost ends thereof and secured to the inner sides of the car, and upon the outer sides of the mine cars, are adapted to dispose their outermost free ends downwardly therefrom and between the ties 12 of the tracks. Arms 19, extended from the pivoted portions of the dogs or elements 17 and at right angles thereto, are adapted for reception within a yoke member 20, included 70 75 upon one end of a turn buckle rod 21 having connection with the outermost projecting end of the equalizer bar 13, through the instrumentality of cables, if desired.

As shown in Figure 2, the devices may be employed in duplicate to engage the rail ties upon the opposite sides of the cars inasmuch as the cars are subjected to heavy loads, such as iron ore, etc. Attaching plates 22, also carried upon the outer sides of the mine car bodies and in line with that of the turn buckle rods 21, are adapted for connection with retractile springs 23 having connection at their opposite ends with the adjacent ends of the yokes 20 whereby dogs or elements 17 will be normally induced to occupy the Figure 1 90 position.

Straps 24, having their ends secured to the outer sides of the car bodies, have their intermediate portions spaced therefrom to permit passage and rocking movement of the dogs or elements therebetween but to restrict movement in either direction beyond a predetermined degree.

After the cars have been loaded at the bottom of the mine, a donkey engine or other 100

draft appliance is employed at the top of the mine shaft to wind up the cable 16 having connection with the tongue 15. The draft action will overcome the tension of the springs 23 whereby the dogs or elements 17 will be disposed parallel with the sides of the car in view of the arm and turn buckle rod connections with the equalizer bar. In the event the cable should break or something should happen to the donkey engine, the slack draft would release tension against the springs 23 which would then contract to shift the dogs or elements 17 to occupy the Figure 1 position. The outermost ends of the dogs or elements would engage the adjacent sides of the ties 12 to prevent retrograde movement of the cars down the mine shaft.

A pin, such as indicated at 25, carried upon one end of the car adjacent the tongue 15, is adapted for selective reception within an opening 26 therein when it is desired to hold the tongue extended, with no draft action thereon, and the dogs 17 in elevated position. Such circumstance may arise when the car was damaged and must be run onto a siding. Said pin would obviously drop out of the opening 26 when a pull was exercised upon the tongue by the cable 16.

The invention is susceptible of various changes in its form, proportions and minor details of construction, and the right is herein reserved to make such changes as properly fall within the scope of the appended claim.

Having described the invention, what is claimed is:—

A safety device for mine cars comprising an equalizer bar slidably mounted within the sides thereof, a tongue carried by the bar and projecting through one end of the car for connection with a draft appliance, dogs rockingly mounted upon the sides of the car for connection at their opposite ends with the ties of the car tracks, arms carried by and projecting from the pivotal connections for the dogs, rods establishing connection between the ends of the equalizer bar and arms of the dogs, spring means carried by the cars and having connection with the rods to yieldingly induce said dogs to engage the ties of the tracks for the car when the draft appliance is rendered inoperative, and straps arranged upon the car to restrict rocking movement of the dogs beyond predetermined degrees.

In testimony whereof I affix my signature.
GEORGE B. PERKINS.
